UNITED STATES PATENT OFFICE.

JOHN A. LUTHER, OF SCHENECTADY, NEW YORK.

PUNCH PRESS.

Application filed May 1, 1920. Serial No. 378,313.

To all whom it may concern:

Be it known that I, JOHN A. LUTHER, a citizen of the United States, residing at Schenectady, in the county of Schenectady, 5 State of New York, have invented certain new and useful Improvements in Punch Presses, of which the following is a specification.

The present invention relates to punch presses and particularly to a die structure, for such presses, and has for its object to provided an improved structure and arrangement for performing a certain type of operation as will be pointed out hereinafter.

10 For a consideration of what I believe to be novel and my invention, attention is directed to the accompanying description and the claims appended thereto.

In the drawing Fig. 1 is a vertical sectional-view through upper and lower die structures embodying my invention; Fig. 2 is a bottom plan view of the upper die structure; Fig. 3 is a detail view of a part of the upper die structure; Figs. 4, 5 and 6 are detail 25 views, and Fig. 7 shows the dies arranged in a punch press.

In the present instance my invention is embodied in a die structure for cutting or stamping a washer from fibrous or similar 30 material, such as asbestos, for example, and depositing such washer in the annular groove of a ring U-shaped in cross section, the same being a step in a process for manufacturing gaskets such as are used in connection with spark plugs. Referring to the 35 drawing, Figs. 4, 5 and 6, 10 indicates a ring U-shaped in cross section and formed from a suitable metal such as copper, and the specific embodiment of my invention 40 illustrated is a die structure for printing or stamping a washer from a sheet of fibrous material 11, preferably asbestos, and depositing the same in the U-shaped ring as shown in Fig. 6, 12 indicating the asbestos 45 washer in the ring.

The lower die structure, which is stationary, comprises a shoe 14 adapted to be fastened to the bed plate of a punch press of usual construction. At the center of 50 shoe 14 is a hole 15 counterbored to form a recess 16 in which is located a holder 17 having a central opening 18 counterbored to form an annular shoulder 19. Projecting from holder 17 is a threadder flange 20 55 against the end of which is fixed an outer die member 21, the same being held in place

by a flanged nut 22 which threads onto the end of flange 20. Located in the counterbored portion of opening 18 and resting against annular shoulder 19 is a head 23 60 from which projects an inner die member 24 located centrally of outer die member 21. Inner die member 24 is a solid post and is held in position by a stud 25 which projects down through opening 18 and has a nut 26 65 on its end which screws up against the bottom of shoe 14. Located in the annular space between die members 21 and 24 is an ejector ring 27 having a head 28 with which engage the upper ends of a number of ejector pins 70 29, three for example. Ejector pins 29 extend down through openings in holder 17 and shoe 14 and at their lower ends are connected to a plate 30 against the under side of which bears the upper end of a spring 31. 75 The lower end of spring 31 rests on a cross bar 32 carried by posts 33 which depend from shoe 14 and the pressure of the spring on the bottom of plate 30 may be adjusted by means of bolt 34 in an obvious manner. 80 Ejector ring 27 has internal and external diameters equal to those of the ring 10 and its upper end has a rounded recess of a shape to receive the bottom of a ring 10.

The upper die structure comprises a holder 85 35 having an axially extending opening 36 counterbored at its upper end to form a recess 37. Fixed to the lower end of holder 35 is an annular die member 39, the interior of which provides a recess 38. In 90 recess 38 is a plunger 40 to which is connected a rod 41 which extends up through opening 36 to a point beyond holder 35. On the upper end of rod 41 is a head 42 and in recess 37 is a spring 43 which at one 95 end engages head 42 and at the other end the bottom of recess 37. At its central portion holder 35 is threaded to receive collar 44 which serves to fasten die member 39 to the holder. Surrounding wall 39 below collar 44 is a supporting member or holder 45 which may slide up and down on wall 39. Supporting member 45 is of substantially rectangular shape as best shown in Fig. 2 and has a longitudinally extending groove 105 46 over which is fastened a cover plate 47. Cover plate 47 terminates short of the right hand side of member 45 and has an opening 48 of slightly greater diameter than the end of wall or die member 39. Groove 46 is of 110 a width slightly greater than the diameter of die member 39 and is of a depth equal to

the thickness of the strip of material from which washers are to be cut or stamped. At the right hand end of groove 46 is a projection 49 which forms a stop. Supporting member 45 and plunger 40 are connected together by a pin 50 which extends entirely through them, wall 39 being provided with slots 51 on opposite sides through which the pin passes. Supporting member 45 and plunger 40 thus move as a unit on wall 39 and are limited in their downward movement by the lower ends of slots 51 and in their upward movement by collar 44. In a recess in plunger 40 is a small spring pressed 10

15 ejector pin 52 shown in detail in Fig. 3. In operation, the dies are placed in a punch press of usual construction, as shown in Fig. 7, the lower die structure having its 20 shoe 14 bolted to the bed plate A of the press, and the holder 35 of the upper die structure being fixed to the reciprocating head B of the press. The press is provided with the usual stop or abutment, usually termed the knock-out lever, and indicated 25 by the line 53 in Fig. 1, which at the upper portion of the strokes holds plunger 40 and supporting member 45 down in their lower-most positions as shown in Fig. 1, pin 50 being at the bottoms of slots 51 and plunger 30 40 being flush with the lower end of die member 39. Fig. 7 illustrates a conventional form of knock-out lever comprising a pivoted arm 54 which engages an upper fixed adjustable abutment 55. A ring 10, 35 U-shaped in cross section, is placed on the lower die structure with its rounded bottom resting in the groove in ejector ring 27 and its open side facing upward. A strip of 40 fibrous material 11, for example, asbestos, is slipped into groove 46 until its end strikes stop 49, the strip being held up by cover plate 47. When the die structures come together, plunger 40 and lower die member 24 which are of the same diameter, engage between them a disk of the asbestos strip and cover plate 47 engages outer die member 21. At this time head 42 on rod 41 has moved away from abutment 53, i. e., from the end of knock-out lever 54, Fig. 7, so said lever 45 is no longer held against abutment 55 but die parts 40 and 45 cannot move relatively to die member 39 because of the asbestos strip 11. Holder 35, however, continues to move with the result that die member 39 50 co-operating with the edges of U-shaped ring 10 cuts a washer from strip 11 and forces it down into the bottom of the ring as shown in Fig. 6. At this time the end of die member 39 enters between the two 55 walls of ring 10 the sides of the ring being supported between the adjacent walls of die members 21 and 24. The washer cut from strip 11 is thus pushed down to the bottom of U-shaped ring 10, ejector ring 27 yielding 60 downwardly somewhat after the bottom is 65

reached. It will be noted that when the die structures come together, the portion of strip 11 on the inside of die member 39 is clamped between parts 24 and 40 of the die structures before the cutting or punching operation begins. The strip of material is thus firmly held during this operation. The die structures now move apart whereupon spring 31 moves ejector ring 27 up to force ring 10 with the washer 12 therein as shown in Fig. 6, off the lower die structure. At the same time spring pressed ejector pin 52 and plunger 40 knock the disk cut from the center of washer 12 out from within die member 39, the parts of the upper die structure assuming again the position shown in Fig. 1. Another U-shaped ring 10 is then placed on the lower die structure and the strip 11 is pushed along groove 46 until its end strikes stop 49. The operation of the die structures 75 is then repeated. As is well understood, the die structures stand at an angle to the horizontal in the punch press so that the parts punched out fall from between them by gravity. The operation can accordingly be 80 made continuous, the operator on each stroke of the punch press feeding forward the strip 11 and placing a new ring 10 on the die structure. Of course, if desired both the rings 10 and the strip 11 or either of them may be fed to the press automatically. 85

In connection with the die structure it is to be noted that the edges of the ring 10, which edges are quite sharp, serve in cutting out the fibre washers from strip 11, the 90 edges of the ring co-operating with die member 39.

Heretofore, so far as I am aware, in the manufacture of gaskets of this character, the asbestos washers have been placed in the 95 U-shaped ring by hand. This has been a very tedious and comparatively expensive method and entailed considerable waste. By my invention I am enabled to perform this work in a punch press and at a very 100 rapid rate thereby materially reducing the cost of manufacture.

It will be understood, of course, that my invention is not necessarily limited to operations carried on in connection with washers but may be applied wherever similar operations are to be performed and wherever it may be found applicable.

In accordance with the provisions of the 105 patent statutes, I have described the principle of operation of my invention, together with the apparatus which I now consider to represent the best embodiment thereof, but I desire to have it understood that the apparatus shown is only illustrative and that the invention may be carried out by other 110 means.

What I claim as new and desire to secure by Letters Patent of the United States, is:

1. In combination, a stationary die struc-

- ture adapted to receive a piece to be worked upon, said piece having upwardly facing edges, a movable die structure having a die member, and supporting means forming a 5 part of said movable die structure for carrying a piece of material from which a part is to be cut by said die member and deposited between said upwardly facing edges.
2. In combination, a stationary die structure having a yielding ejector member adapted to receive a piece to be worked upon, said piece having upwardly facing edges, a movable die structure having a die member, and means for supporting a strip of 10 material between said die structure from which a part is to be cut by said movable die member and the edges of said piece and deposited between said upwardly facing edges.
- 20 3. In combination, a stationary die structure having a yielding ejector member adapted to receive a piece to be worked upon, said piece having upwardly facing edges, a movable die structure having a die member, and a supporting member forming a 25 part of the movable die structure and having a groove for holding the end of a strip of material directly under said die member, said movable die member co-operating with 30 the edges of said piece to be worked upon to cut a part from said strip and deposit it between such edges.
4. In combination, a stationary die structure having a yielding ejector member 35 adapted to receive a piece to be worked upon, said piece having upwardly facing edges, a movable die structure having a die member, a supporting member forming a part of the movable die structure and having a groove 40 for holding the end of a strip of material directly under said die member, said movable die member co-operating with the edges of said piece to be worked upon to cut a part from said strip and deposit it between such 45 edges, and means forming part of the die structure for clamping the strip during the cutting operation.
5. In combination, a die structure comprising an annular ring, adapted to support a ring U-shaped in cross section, a second die structure comprising an annular die member of the same size as the U-shaped ring, a supporting member for holding a piece of material under said annular die member, and means forming parts of the die 50 structure for clamping between them the portion of said piece of material which lies inside the inner edge of said die member, said die member co-operating with the edges of said U-shaped ring to cut a washer from 55 said strip and deposit it in the bottom of the ring.
6. In combination, a stationary die structure comprising an inner die member, a yieldable annular ejector ring surrounding 60 it and adapted to support a ring, U-shaped in cross section, a movable die structure comprising an annular die member of the same size as the U-shaped ring, an ejector plunger in said die member, and a supporting 65 member surrounding said die member and adapted to hold a strip of material beneath it, said inner die member and plunger holding said strip between them when the dies come together and said annular die 70 member co-operating with the edges of said U-shaped ring to cut a washer from said strip, the end of said annular die member entering the space between the walls of 75 said U-shaped ring to deposit such washer 80 against the bottom of the ring.
7. In combination, a pair of relatively 85 movable die structures one of which is adapted to receive a piece to be worked upon, said piece having upwardly facing edges, and the other of which has a die member, and means for supporting a strip of material between said die structures, the die member co-operating with the edges of said 90 piece to cut a part from the strip and deposit it between such edges.

In witness whereof, I have hereunto set my hand this 30 day of April, 1920.

JOHN A. LUTHER.
